(57) **CLAIM**

The ornamental design for an electronic cable junction, as shown and described.

DESCRIPTION

FIG. 1 is a Top View of the electronic cable junction according to the present invention.

FIG. 2 is a bottom view of the electronic cable junction of FIG. 1.

FIG. 3 is a front view of the electronic cable junction of FIG. 1.

FIG. 4 is a rear view of the electronic cable junction of FIG. 1.

FIG. 5 is a right side view of the electronic cable junction of FIG. 1.

FIG. 6 is a left side view of the electronic cable junction of FIG. 1; and,

FIG. 7 is a front elevational perspective view of the electronic cable junction of FIG. 1.

The broken lines through the drawing figures are included for the purpose of illustrating environmental structure only and form no part of the claimed design.
